UNITED STATES PATENT OFFICE.

CARL O. HEDSTROM, OF SPRINGFIELD, MASSACHUSETTS.

INTERNAL-COMBUSTION ENGINE

No. 895,754.

Specification of Letters Patent.

Patented Aug. 11, 1908.

Application filed October 30, 1907. Serial No. 399,862.

To all whom it may concern:

Be it known that I, CARL O. HEDSTROM, a citizen of the United States of America, residing at Springfield, in the county of Hampden and State of Massachusetts, have invented new and useful Improvements in Internal-Combustion Engines, of which the following is a specification.

This invention relates to improvements in internal combustion engines and is particularly confined to the valve mechanism for operating the inlet and exhaust valves that control the passages to and from the combustion chamber.

Broadly, the invention consists in associating with the cam shaft of the engine a mechanism by which both of said valves may be operated therefrom thus simplifying the engine in this particular part.

In the drawings forming part of this application,—Figure 1 is a partial vertical sectional view through the valve-stem of the exhaust valve of the engine, also showing a portion of the crank casing broken away for illustrating the cam-operating mechanism. This view shows both the exhaust and inlet valves closed. Fig. 2 is a view similar to Fig. 1 but showing only the exhaust valve open, the cam for operating the same being in one position, and Fig. 3 shows a view similar to Fig. 2 but with the exhaust valve closed and the inlet valve open, the cam for operating the valve being in another position.

Referring to the drawings in detail, *a* designates the cylinder of the engine; *b* the crank casing; *c* the cam shaft to which is secured the valve-operating cam *d*. Pivotally secured to the crank casing *b* at the point *e* is a cam lever *f* the lower side of which is provided with an antifriction roller *g*. Located above the cam lever *f*, and loosely mounted in the frame of the machine is a rod *h*, the upper end of which engages a socket *h*¹ in the arm *i* which is made integral with the lower end of the inlet valve operating rod *j*, as shown.

Loosely mounted in an opening in the arm *i* of the rod *j* is a rod *k* that engages at its upper end an abutment *k*¹. Encircling the rod *k* is a spring *m* which is normally placed under compression, its lower end engaging a shoulder portion *m*¹ on the arm *i*, and its upper end engaging a shoulder *m*² on the rod *k*. The action of this spring is always downward so that the rod *j* will be operated when the

rod *h* is permitted to fall, as will be fully set forth in describing the operation of the invention. The upper end of this rod *j* is curved inward at *o* and has mounted in the upper end thereof an adjustable screw *p* that is provided with a lock-nut *q* so that after adjustment of the screw *p* the same may be locked securely to the rod *j*. Loosely mounted in the plug *r* is a loosely fitting pin *q*¹. When the rod *j* rises, as shown in Fig. 2, the end of the adjustable screw *p* will leave the upper end of the pin *q*¹, as shown; but when the rod *j* is permitted to move downward, as shown in Fig. 3, the upper end of the pin *q*¹ will be struck by the lower end of the adjustable screw *p* thus opening the inlet valve *t*, as clearly shown in Fig. 3. In order to reduce the friction of the rod *j* during its reciprocating movements as much as possible, I provide an anti-friction roller *o*¹.

The inlet valve has its stem slotted for receiving a pin *u* which engages the sleeve *v*, the lower end of which is of less diameter in order to form a shoulder portion for receiving the expansive spring *w*. The lower end of this spring rests on the bridge-piece *x*. The expansive spring *w* normally holds the inlet valve *t* closed.

It will be observed that the upper end of the pin *q*¹ and the adjustable screw *p* are slightly separated from each other by a small space, designated by *y*.

The inlet valve *t* is shown in Fig. 1 in a closed position and the stem 2 of the exhaust valve is then extended downwardly into close proximity to the arm *i* which, as stated, is made integral with the main portion of the rod *j*.

A spring 3 engages, at its opposite ends, a shoulder 4 and a plate 5 so that this spring acts normally to hold the exhaust valve 2 closed.

Referring now to the construction of the cam *d*: a curved part 6 is concentric with the axis of the shaft *c* and the roller *g*, when in contact with this part, will not rise or fall. The direction of rotation of the cam *d* is indicated by the arrow 7. Considering the roller *g* on the lever *f* as in engagement with the high portion 8 of the cam *d* the exhaust valve 2, as shown in Fig. 2, will be opened allowing the burned gases to escape. The inlet valve *t* will not be operated as the adjustable screw *p* will be elevated above the pin *q*¹, as shown. A further rotation of the cam *d* will bring the surface 9 into contact

with the roller *g*, as shown in Fig. 3. This position of the cam will permit the rod *h* to move downward, as shown in this figure, and also at the same time the expansive force of 5 the compression spring *m* will be exerted on the rod *j* downward carrying with it the pin *q* by reason of the adjustable screw *p* in the upper end of the rod *j* striking this pin. The inlet valve *t* is therefore opened 10 and the exhaust valve *z* closed. This portion of the cam *d* is made wavy in order to impart to the roller *g* as easy a motion as possible. Further movement of the cam *d* will permit the roller *g* to engage the surface 15 6 whereby both valves *t* and *z* will be closed, and during this period of rotation work is being performed in the cylinder. The roller *g* next engages the high portion 8 of the cam after passing over the nearly straight surface 20 10 and opens the exhaust valve *z* as before described, thus completing the cycle of operations.

What I claim, is:—

1. In combination with a cam-shaft of an 25 internal combustion engine, a cam thereon, a cam-lever as *f*, a roller as *g*, engaging the cam, a rod as *h* engaged by the cam-lever, an operating rod having a socket in one end thereof and engaged by the upper end of the 30 rod *h*, a spring for actuating the operating rod, an inlet-valve, an exhaust valve, the

spring serving to open the inlet-valve when the cam-lever engages a certain portion of the cam, and the rod *h* serving to open the exhaust-valve when the inlet-valve is closed 35 and when the cam-lever engages another portion of the cam, as described.

2. In combination with a cam-shaft of an internal combustion engine, a cam thereon, a cam-lever as *f*, a roller as *g* engaging the 40 cam, a rod as *h* engaged by the cam-lever, an operating rod having a socket in one end thereof and engaged by the upper end of the rod *h*, a spring for actuating the operating rod, an inlet-valve, an exhaust valve, the 45 spring serving to open the inlet-valve when the cam-lever engages a certain portion of the cam, and the rod *h* serving to open the exhaust valve when the inlet-valve is closed and when the cam-lever engages another 50 portion of the cam, as described, the operating rod being provided with an opening therethrough, a rod as *k*, engaging the opening in the operating-rod, the operating spring encircling the rod *k*, its opposite ends 55 engaging a shoulder as *k*¹ and a part of the operating-rod, as described.

CARL O. HEDSTROM.
